SPLIT WELT CEMENTING MACHINE

Wilbur L. MacKenzie, Beverly, Mass., assignor to
 United Shoe Machinery Corporation, Borough
 of Flemington, N. J., a corporation of New
 Jersey

Application September 16, 1938, Serial No. 230,296

8 Claims. (Cl. 12—80)

This invention relates to machines for applying cement to work parts and is herein illustrated as embodied in a machine for cementing the adjacent faces of the flap portions of a split welt secured to a lasted shoe, which machine is of the type disclosed in United States Letters Patent 2,098,253, granted November 9, 1937, on an application filed in my name. It is to be understood, however, that the invention is not limited to machines of that particular character.

In the manufacture of certain types of shoes such as so-called "stitchdown" shoes, it is customary to attach to a lasted shoe of that type a welt, the edge of which has been split or channeled, one split portion or flap having been secured to the lasted shoe by means of stitches and the other split portion later serving to hide the stitches by being adhesively secured to the first-mentioned split portion after the sewing of that portion. In order to perform a satisfactory splitting operation on the welt and in order to raise one of the split portions of the welt to permit the attachment of the other portion to the shoe, it is preferable that the welt be in temper. However, as a result of the tempering of the welt, the raised split portion when drying out, which usually occurs after the welt is attached to the shoe and before cement is applied to the channeled or split welt, becomes rather wrinkled and wavy, and hence presents a distinct problem for the application of a uniform coat of cement thereto.

It is, therefore, an object of the invention to provide improved means for applying cement to the angularly disposed faces of a channel in a work piece, particularly in a strip such as a welt secured to a lasted shoe, in such a manner that the surfaces of the work to be cemented will be coated with a uniformly thick layer of cement regardless of irregularities in the said surfaces and that soiling of other parts of the work by the application of cement beyond the area to be coated is successfully prevented.

In accordance with one feature of the invention, the illustrated machine is provided with a tapered nozzle to apply cement to the channel of a split welt with which nozzle there cooperates a member for holding one part of the split welt against the nozzle during the entire cement-applying operation progressing along the channel of the welt.

In accordance with another feature of the invention, there is provided in the illustrated machine a driven feed wheel which engages the upper of the shoe to which the split welt has been secured to as to cause the split welt to be moved past the nozzle, the feed wheel being arranged on the same side of the nozzle as the above-mentioned member for holding one part or flap of the split welt against the nozzle. In the illustrated machine, the flap-holding member is in the form

of a finger, mounted on a support pivotally secured to the nozzle. The finger support is engaged by spring means to maintain the finger in an inoperative position and is actuated by means of an operator-controlled mechanism to move the finger into work-engaging position.

The above and other features of the invention will now be more particularly described with reference to the accompanying drawing and thereafter pointed out in the claims.

In the drawing:

Fig. 1 is a side view of a preferred embodiment of the invention showing a machine with its various moving parts in their operative positions;

Fig. 2 is a perspective view of the operating tools of the machine;

Fig. 3 is a front view of the operating tools of the machine;

Fig. 4 is a detailed view of part of the operating tools with a piece of work, in section, presented thereto; and

Fig. 5 is a view similar to Fig. 1 but showing the parts in their inoperative positions.

The invention is illustrated as embodied in a machine of the type described in Letters Patent of the United States No. 2,098,253 mentioned above and reference may be made to that patent for a description of the machine structure not fully shown herein. The machine as illustrated herein is especially adapted to apply cement to the two angularly disposed faces of a channel in a welt W (Fig. 4) produced as a result of channeling or splitting the welt at a certain distance from its top face in a direction more or less parallel to the said face, the split beginning at one edge face of the welt and terminating near the other edge face thereof thereby substantially dividing the welt into two flap portions which are still integral at one edge. As illustrated in Fig. 4 one flap portion of a welt, split or channeled as described, is secured to a lasted shoe L by means of a seam S which attaches a sole O to an upper U, the other flap of the welt, after having been adhesively attached to the first mentioned flap, serving to hide the seam S.

For the purpose of applying cement to the channel portion of the split welt, the illustrated machine is provided with cement-applying means 40, flap-supporting means 52, and work-feeding means 60 the construction and function of which will now be described. The illustrated machine has a frame 10 to which, as in the machine illustrated in the above-mentioned United States Letters Patent, is secured a carrier 12 supporting the work-engaging instrumentalities of the machine. The lower portion of the carrier 12 is provided with laterally extending parallel, spaced flanges 14 (Figs. 2 and 3) which extend laterally from the carrier and support overhanging portions 15 of a T-shaped block 16 fitted in the space between the flanges. The block 16 is hollow and 60

carries at its lower extremity a hollow nozzle stem 18 (Fig. 2) which is in communication with the hollow interior of the block 16.

For the purpose of quickly mounting and dismounting the block 16 and the machine parts carried by it, there is provided a curved clamping member 20 pivotally secured at 22 to the lower end of the block 16, the forked left end (Fig. 3) of the clamping member 20 engaging the lower surfaces of the flanges 14. The upwardly extending right end (Fig. 3) of the clamping member 20 carries a hand screw 24 engaging the upper portion of the said block 16. As will be seen, rotation of the screw 24 so as to move the upwardly extending right end of the clamping member 20 (Fig. 3) away from the upper end of the block 16 causes the left forked end of the clamping member 20 to press firmly against the flanges 14 thereby clamping the portions 15 of the block 16 firmly against the flanges 14.

At its upper end, the block 16 is in communication with a conduit 26 provided at its lower end with a flange 28 firmly secured to the top face 25 of the block 16. The conduit 26 through which cement is pumped under pressure into the nozzle stem 18 is provided with a shut-off valve 30 which is controlled by mechanism to be described later. The upper end of the conduit 26 is threaded 30 in a T-fitting 32, one end of which supports a pressure gage 34 and the other end of which is in communication with a flexible tube 36 through which the cement is pumped under pressure.

To adapt the machine particularly to apply cement to split welts as described, it is provided with a nozzle 40, such as that illustrated in Figs. 6 and 8 of the above-mentioned patent, especially suitable for that purpose. The nozzle has a hollow main portion which is secured by screws 39 or 40 the like to a flange 38 provided at the lower end of the above-mentioned nozzle stem 18. The lower end 42 of the nozzle is tapered as seen in side elevation (Figs. 1 and 4) and is of a substantially triangular shape as seen from the front 45 of the machine (Fig. 3). The leading edge of the nozzle end 42 is provided with a hole 43 (best shown in Figs. 2 and 4) through which cement is extruded and applied to the channel bottom of the split welt. Secured to a lug provided at 50 the trailing end of the main nozzle portion is a small plate 44 the lower end of which is tapered in conformity to the tapered shape of the nozzle end 42 and overlies a perforated intermediate plate 41. The said lower end of the plate 44 is spaced from the plate 41 and the lower end of the latter is maintained at a certain distance from the open trailing portion of the nozzle end 42 thereby providing two, parallel, substantially V-shaped slots through which the cement is applied 55 to the angularly disposed split faces of the welt.

To support the free flap portion F of the split welt, that is the flap portion which is not secured to the lasted shoe by the seam S, during the 60 cement-applying operation and particularly to hold that portion which has a wavy irregular shape against the cement-applying nozzle so that a uniform coat of cement may be applied thereto, there is provided a flap-supporting means 52 65 which, as illustrated, is in the form of a finger. For supporting and actuating this finger, the nozzle stem 18 carries a block 45 to which is pivotally secured at 46 (Figs. 2 and 3) a two-armed lever 48. The right arm (Fig. 3) of said lever 48 is provided with a lug 50 (Fig. 2) in

which is secured, as by a draw-bolt 51, a finger 52 serving to engage and support the said flap portion of the split welt and to hold it against the nozzle during the cement-applying operation. The upper surface of the left arm (Fig. 3) of this lever 48 is engaged by a spring-pressed plunger 54 mounted for vertical movement in a bore in the carrier 12 and tending to depress the left arm of the lever 48 thereby holding the flap-supporting finger 52 in the position shown in full lines 10 in Fig. 3. For the purpose of swinging the lever 48 in a clockwise direction as seen in Fig. 3 against the resistance of the plunger 54 to move the finger 52 into its flap-engaging operative position illustrated in broken lines, the end of the left arm of the lever 48 is pivotally secured to a link 56, the upper end of which is pivotally secured to a bell crank lever 58 (Fig. 1) pivoted to the carrier 12. The bell crank lever 58 is operated by mechanism to be described later.

For the purpose of positioning and feeding the work presented to the machine, there is provided, as in the machine of the above-mentioned United States Letters Patent, a feed wheel 60 which is positively driven and which is carried by a support 62. A spring 65, one end of which is secured to the machine frame and the other end of which is secured to the said support 62, tends to hold the support 62 and the feed wheel 60 in an elevated inoperative position. The support 62 is connected 30 to treadle operated mechanism which upon depression of the treadle causes the support to be swung downwardly against the tension of the spring 65 to hold the feed wheel 60 yieldingly in engagement with the work, in the present case 35 in engagement with the side portions of the upper U of the lasted shoe.

The above-mentioned treadle controlled mechanism includes a treadle rod 70 the upper end of which is secured to a link 72. The lower end 40 of the link 72 has a slot 73 engaged by a pin 74 secured to a lever 76 normally held in its upper inoperative position by a spring 77. In the inoperative position of these machine parts the pin 74 is at the lower end of the slot 73. Upon 45 depression of the treadle (not illustrated) the treadle rod 70 and the link 72 are moved down. The lever 76 at first remains stationary due to the lost motion provided by the slot 73. Upon engagement of the upper end of the slot 73 with the pin 74 and upon continued downward movement of the treadle rod 70, the lever 76 is swung downwardly against the tension of its spring 77. The right end (Fig. 1) of the lever 76 is connected by means of a link 78 to a lever 80 secured to and extending laterally from a rod 82 which by means of a universal joint 84 is connected to a rod 86 the rod 86 being connected by means of a universal joint 88 to the stem of the above-mentioned valve 30 that controls the flowage of 50 cement through the conduit 26 into the nozzle 40. As will be seen, downward swinging movement of the lever 76 causes a rocking movement of the rods 82, 86 which is imparted to the valve 30 and which causes the valve 30 to be opened.

The illustrated machine is also provided with means actuated by the above-mentioned treadle-controlled mechanism of the machine to cause movement of the flap-supporting finger 52 into operative position upon depression of the treadle. 70 As illustrated in Fig. 1, the upper end of the link 72 is pivotally secured at 83 to the right arm of a three-armed lever 85 pivotally secured to the machine frame. A forked upwardly-extending arm of the lever 85 engages a pin 87 carried by the 75

lower end of a lever 89 the upper end of which is pivotally mounted in the machine frame. Near its lower end the lever 89 is connected to a horizontal rod 90 the left end of which (Fig. 1) is pivotally secured to the upwardly extending arm of the aforementioned bell crank lever 58 that controls the movement of the finger 52. The swinging movement of the three-armed lever 85 in clockwise direction (Fig. 1) by the depression of the treadle is limited by the engagement of an arm 92 of the lever 85 with a fixed abutment 94.

As will be seen, depression of the treadle serves to move the driven feed roll 60 into engagement with the work and simultaneously causes the finger 52 to be moved into operative position. Thereafter, that is after the pin 74 carried by the lever 76 has been engaged by the upper end of the slot 73 of the link 72, the valve 30 is opened with the result that cement is extruded through the nozzle into the channel portion of the welt, shortly after the feed movement of the work has been initiated.

The operation of the illustrated machine will be apparent from the foregoing description but will be briefly summarized now. A lasted shoe to which has been secured a channeled or split welt is presented to the machine with the bottom portion of the shoe extending in a vertical direction and with the tread face of the outsole facing the operator. The shoe is so presented that the tapered end portion 42 of the nozzle 40 engages within the channel portion of the welt, as illustrated in Fig. 4. Upon depression of the treadle, the feed wheel 60 which is continuously driven by the power means of the machine is moved into yielding contact with the lasted upper of the shoe and simultaneously the finger 52 is moved into contact with the outer face of the (in Fig. 4) right flap portion F of the welt to hold that flap portion against the nozzle. After the upper end of the slot 75 has engaged the pin 74, the lever 75 is swung downwardly and the valve 30 is opened and cement is extruded into the channel portion of the split welt.

By reason of the feed action of the feed wheel 60 the entire split welt is moved past the nozzle and its channel portion is coated with cement whereupon the operator upon releasing the treadle causes the valve 30 to be automatically shut by reason of the fact that the lever 76 is immediately swung upwardly by the strong spring 77 (Fig. 1). The upward movement of the treadle rod 78 by its spring also causes a return movement of the rod 90 toward the left of Fig. 1, thereby swinging the finger 52 into its inoperative position with the assistance of the spring-pressed plunger 54. Finally, the upward movement of the treadle rod 78 also permits the spring 65 to move the support 62 of the feed roll 60 into its inoperative upper position.

Having described my invention, what I claim as new and desire to secure by Letters Patent of the United States is:

1. In a machine for cementing the angularly disposed faces of a channel in a strip split to form two flaps, one of which is secured to a piece of work, a tapered nozzle to apply cement to the said angularly disposed faces, and means for holding the loose flap of the said strip in cement-receiving contact with one side of the nozzle during the cement-applying operation.

2. In a machine for cementing the channels of split welts attached to lasted shoes, a tapered nozzle for engaging the channel of a split welt, a driven feed wheel on one side of the nozzle, the

said wheel engaging the upper of a lasted shoe presented to the nozzle to move the split welt past the nozzle, and means located between the nozzle and the feed wheel for holding one portion of the split welt against the nozzle.

3. In a machine for cementing split welts attached to a lasted shoe, a tapered nozzle for engaging the channel of a split welt, a driven feed wheel on one side of the nozzle engaging the upper of a lasted shoe presented thereto to move the split welt past the nozzle, and a finger located at the same side of the nozzle as the feed wheel for holding one portion of the split welt against the nozzle.

4. In a machine for cementing split welts, a nozzle for engaging a split welt, a driven feed member for causing the split welt to be moved past the nozzle, means located between the nozzle and the feed member for holding one portion of the split welt against the nozzle, spring means for holding the said holding means in inoperative position, and operator-controlled means to move the said holding means into work-engaging position.

5. In a machine for cementing split welts, a nozzle for engaging the channel of a split welt, means for controlling the flow of cement through said nozzle, a driven feed wheel for causing the split welt to be moved past the nozzle, operator-controlled means for moving the feed wheel into engagement with the work and for operating the said means for controlling the flow of cement through said nozzle, and a finger located between the nozzle and the feed wheel for holding one portion of the welt against the nozzle, the said operator-controlled means also serving to move the said finger into work-engaging position.

6. In a machine for cementing split welts, a nozzle for engaging the channel of a split welt, a finger for holding one portion of the split welt against the nozzle, a support for said finger pivotally mounted on the nozzle, spring means engaging said support to maintain the finger in inoperative position, and operator-controlled means for swinging said support to move the said finger into work-engaging position.

7. In a machine for cementing split welts, a nozzle for engaging the channel of a split welt, a driven feed wheel for causing the split welt to be moved past the nozzle, a finger for holding one portion of the split welt against the nozzle, a common support for the nozzle and the finger, and means for clamping both the nozzle and the finger to the said common support.

8. In a machine for cementing the channels of split welts attached to lasted shoes, a tapered nozzle for engaging the channel of a split welt, a valve for controlling the flow of cement through said nozzle, a driven feed wheel on one side of the nozzle engaging the upper of a lasted shoe presented to the nozzle to move the split welt past the nozzle, a finger located between the nozzle and the feed wheel for holding one portion of the split welt against the nozzle, a support for said finger pivotally mounted on the nozzle, spring means engaging said support to hold said finger in inoperative position, and treadle-controlled means for maintaining the feed wheel in yielding engagement with the work and for operating said valve to cause cement to be extruded through the nozzle, said treadle-controlled means also serving to move the said support against the pressure of the spring means engaging it to move said finger into work-engaging position.
